UNITED STATES PATENT OFFICE.

FRANK A. SEBRING, OF SEBRING, OHIO, ASSIGNOR TO THE LIMOGES CHINA COMPANY, OF SEBRING, OHIO, A CORPORATION OF OHIO.

DESIGN FOR A CUP.

Application filed July 8, 1927. Serial No. 22,703. Term of patent 3½ years.

To all whom it may concern:

Be it known that I, FRANK A. SEBRING, a citizen of the United States, residing at Sebring, in the county of Stark and State of Ohio, have invented a new, original, and ornamental Design for Cups, of which the following is a specification, reference being had to the accompanying drawing, forming part hereof.

Fig. 2, a side elevation of the cup; and

Fig. 3, a section on the line 3—3, Fig. 2.

I claim:

The ornamental design for a cup, as shown.

FRANK A. SEBRING.
